His Attorney.

UNITED STATES PATENT OFFICE.

CHRISTIAN STEENSTRUP, OF SCHENECTADY, NEW YORK, ASSIGNOR TO GENERAL ELECTRIC COMPANY, A CORPORATION OF NEW YORK.

METHOD OF MAKING BLADE RINGS FOR ELASTIC-FLUID TURBINES.

Application filed July 3, 1920. Serial No. 393,930.

To all whom it may concern:

Be it known that I, CHRISTIAN STEENSTRUP, a citizen of the United States, residing at Schenectady, county of Schenectady, State of New York, have invented certain new and useful Improvements in Methods of Making Blade Rings for Elastic-Fluid Turbines, of which the following is a specification.

10 The present invention relates to elastic-fluid turbines, and is particularly applicable to turbines of the radial flow type which comprise two opposed rotors which revolve in opposite directions and carry axially extending interleaving blade rings through which the motive fluid flows in a radial direction. Each blade ring is attached at one end to a rotor, the other end being free, and the attaching means may comprise suitable 15 expansion rings such as are now known in this art. My invention is not necessarily limited to such turbines, however, but may be utilized in any type of turbine to which it may be found applicable.

20 The blade rings, since they are carried at one end only and extend axially, must be quite stiff and the same are accordingly provided with rings at their ends which serve to hold the ends of the blades, and with reinforcing rings between their ends. There 25 may be one, two or more reinforcing rings, according to the axial length of the blade ring and they serve to divide the blade ring into a number of blade sections. A completed blade ring thus has the appearance of 30 a number of spaced rings with lengths of blading between them.

The object of my invention is to provide an improved method of making a turbine 35 element such as a blade ring of the above described type and for a consideration of what I believe to be novel and my invention, attention is directed to the accompanying description and the claims appended thereto.

40 In the drawing wherein I have illustrated my invention applied to the building of a blade ring, Fig. 1 is a perspective view of a length of blading; Fig. 2 is a perspective view of a spacing and reinforcing piece; Fig. 3 is a perspective view illustrating the 45 initial building up of a blade ring structure; Figs. 4, 5, 6 and 7 are views illustrating steps which may be used in carrying out my method; Fig. 8 is a diametrical sectional view of

a completed blade ring; and Fig. 9 is a side elevation of a spacing ring.

In carrying out my invention I provide bucket or blade lengths 10 as shown in Fig. 1 of a length equal to the total axial length of the blade ring to be made. Bucket lengths 50 10 may be cut from strips of bucket or blade material which have been suitably shaped as by drawing, rolling or other means, and can be thus provided in quantity at a low manufacturing cost. I also provide spacing 55 blocks 11 as shown in Fig. 2 which can be readily made by providing bars of the correct shape which are cut up into blocks, or by stamping or punching them from suitable strip material. I then build up a blade ring 60 from these blade lengths and spacing blocks, the blades and blocks being first fastened together in what may be termed an initial or temporary manner by arc welding, spot welding or other suitable means, after which 65 the parts are permanently united into an integral structure by fusion of metal, as by brazing, welding or the like. Preferably I employ the method of uniting as set forth in my application Serial No. 354,014, filed 70 January 26, 1920. This method comprises placing the assembled structure in a suitable muffler containing a reducing atmosphere such as hydrogen and heating it, an alloying metal such as copper having been previously 75 placed adjacent to the joints between the parts to be united. When heated to a suitable temperature, the copper enters the interstices between the parts and unites them to each other to form in substance an integral 80 structure. However, my invention is not necessarily limited to this specific method of uniting the parts and it is to be understood that by the term "fusion of metal" I mean the particular method referred to or other 85 suitable method.

I will now describe the specific method I now prefer for building up a blade ring in accordance with my invention. In the first instance I stand a ring of blades 10 on one 90 end on a support with spacing blocks 11 resting on the support between the lower blade ends, the ring of blades having a diameter approximately equal to that desired for the completed blade ring. As a convenient form 95 of support I may utilize a ring 12 as shown in Fig. 3 which is provided with openings 13 of a size to receive the ends of blades 10, the

openings being spaced apart a distance equal to the spacing required for the buckets of the blade ring. As is clear from Fig. 3, the blocks 11 are wider than blades 10 and have 5 curved surfaces to conform to the contour of the blades. After a ring of blades has been built up with spacing blocks between their lower ends, I then place a temporary spacing ring 14 around the lower end of the 10 blades, which ring is of a width equal to the spaces desired between the reinforcing rings. Spacing ring 14 may be in the form of a split spring ring, as shown in Fig. 9, and it may be spread slightly, slipped down over 15 the bucket ring from the top and then permitted to spring together. It is positioned so as to rest on the upper surfaces of the first ring of spacing blocks 11. After spacing ring 14 is in place I then arrange another 20 row of spacing blocks 11 around the bucket ring, the same resting on and being spaced from the first row by ring 14. A second spacing ring 14^a is then placed on this second row of spacing blocks and another 25 row of spacing blocks arranged above it. This is repeated until the spacing rings and blocks are built up to the top edge of the blades. In the present instance and by way of example I have shown in Fig. 3 two spacing 30 rings 14, 14^a, and three rows of blocks 11, but obviously any desired length of blade ring may be built up in a similar manner.

If found desirable, in assembling a blade ring structure after the manner described, 35 I may build it up around a collapsible sleeve as shown in Fig. 4. Such a sleeve may comprise a cylinder 15 having a flange 16 at its lower end and a cone-shaped opening through it. In cylinder 15 are axially extending slots 17, some of which extend from the top of the cylinder nearly to its bottom, and others of which extend from the bottom nearly to its top. These slots permit the 40 sleeve to be compressed. In assembling a blade ring structure on such a sleeve, I may build it up directly on flange 16 after the manner already described in connection with Fig. 3, or I may first place a ring 18 similar to ring 12 on flange 16 and then build the 45 blade ring structure, the lower ends of the blades resting in slots in ring 18.

After a blade ring structure has been assembled in the manner described, a collapsible sleeve 20 is placed around the structure, 50 as shown in Fig. 5, after which the inner collapsible sleeve 15 is removed if the structure has been previously built up around it as shown in Fig. 4. The collapsible sleeve 20 may be similar in structure to sleeve 55 15 except that it has a cylindrical inner surface and a conical outer surface. Slots 21 which extend part way through sleeve 20 from its opposite ends permit it to collapse 60 when a ring 22 having a conical inner surface is forced down over its outer conical

surface. Sleeve 20 is now collapsed so as to compress the built up blade ring structure and bring the blades and spacing blocks into firm engagement with each other, the structure being preferably forced into a 70 slightly smaller diameter than the diameter which the blade ring is to have when completed.

While held thus compressed by sleeve 20 the structure is welded together in a temporary or initial manner in any suitable way, as by being welded on an automatic electric welding machine and in Fig. 6 such welding is indicated at 23. This welding serves as a temporary means for holding the 75 built up structure together and the collapsible sleeve 20 and spring rings 14 are now removed and the structure fastened together still more securely as by further welding, or by fusion of metal as by brazing or the like. The structure is now again inserted into collapsible sleeve 20 and the sleeve is compressed to make the structure round, after which the sleeve with the structure 80 therein is mounted on a plate 19 which in turn is fastened to a boring mill. A cut is then taken through the inside of the structure to give it a smooth even surface as seen in Fig. 7.

Following this the structure is again removed from collapsible sleeve 20 and is mounted on an expanding sleeve or mandrel 24, similar to sleeve 15, and adapted to be expanded by driving a cone-shaped head 25 through it. While mounted on this mandrel I now turn grooves 26 through the spacing blocks and also the bucket section and wind in such grooves a steel ribbon 27 of high strength material. In Fig. 7 for purposes of illustration, the two lower grooves 26 are shown with ribbon 27 wound therein, while the uppermost groove 26 is shown with the ribbon not yet wound therein.

After ribbon has been wound in all the 95 grooves, the structure is removed from the mandrel and permanently united in a final manner by fusion of metal so as to form in substance a permanent integral unit. Preferably this final uniting is made in accordance with the method set forth in my prior application already referred to herein. At this time the structure may be heat treated 100 also if found desirable.

Having been finally united by fusion of metal, the structure is again mounted on an expanding mandrel as shown in Fig. 7 and expanded until the pitch diameter of the blades is correct. Or should it happen that the structure is too large it may have a collapsible sleeve or mandrel as shown in Fig. 6 placed around it and be compressed to the correct diameter. The structure is now suitably finished inside and outside and a groove 115 28 turned in one end to receive an expansion ring by which it is attached to the rotor, 120 130

if such is the case. The completed structure would then have the appearance shown in Fig. 8.

In accordance with the provisions of the patent statutes, I have described the principle of operation of my invention, together with the particular method which I now consider to represent the best manner for carrying it out, but I desire to have it understood that the particular method described is only illustrative and that the invention may be carried out with such modifications as come within the scope of the appended claims.

15 What I claim as new and desire to secure by Letters Patent of the United States, is,—

1. The method of manufacturing a blade ring of the type comprising a plurality of spaced, parallel reinforcing rings with lengths of blading between them which comprises taking lengths of blading and spacing blocks, building up the complete structure therefrom, the blocks being arranged between the blade lengths at the points where the reinforcing rings are to occur, and finally uniting the build-up structure by fusion of metal.

2. The method of making a blade ring which comprises building up the structure complete from lengths of blading and spacing blocks, uniting the built-up structure in an initial manner, and then permanently uniting it into an integral structure by fusion of metal.

3. The method of making a blade ring which comprises taking lengths of blading substantially equal to the total length of the completed blade ring and spacing blocks, building up a ring of blades with rows of spacing blocks at the two ends of the blades and at one or more intermediate points, uniting the built-up structure in a temporary manner, and then permanently uniting it into an integral structure by fusion of metal.

4. The method of making a blade ring which comprises taking lengths of blading substantially equal to the total length of the completed blade ring and spacing blocks, building up a ring of blades with rows of spacing blocks at the two ends of the blades and at one or more intermediate points, placing a collapsible sleeve around the built-up structure to press the structure together, welding the structure together in an initial manner, and then removing it from the sleeve and permanently uniting the structure by fusion of metal.

5. The method of making a blade ring which comprises building up a structure from lengths of blading and rows of spacing blocks, said rows of spacing blocks being spaced by rings encircling the blades, compressing the built-up structure by means

of a collapsible sleeve, welding the spacing blocks of each row together, then removing the sleeve and permanently uniting the structure by fusion of metal.

6. The method of making a blade ring 70 which comprises building up a structure from lengths of blading and rows of spacing blocks, said rows of spacing blocks being spaced by rings encircling the blades, compressing the built-up structure by means of 75 a collapsible sleeve, welding the spacing blocks of each row together, cutting annular grooves around the rings of spacing blocks, winding metallic ribbon therein, and permanently uniting the structure by fusion of 80 metal.

7. The method of making a blade ring which comprises building up a structure from lengths of blading and rows of spacing 85 blocks, said rows of spacing blocks being spaced by rings encircling the blades, compressing the built-up structure by means of a collapsible sleeve, welding the spacing blocks of each row together, removing the sleeve and permanently uniting the structure by fusion of metal, and then bringing it to correct diameter by expanding it or compressing it by means of expanding or collapsible sleeves.

8. The method of bringing a built-up blade ring to correct pitch diameter, which comprises inserting a split sleeve in the ring and expanding the sleeve and then placing a split sleeve around the ring and compressing it.

9. The method of making a blade ring which comprises building it up around a sleeve from blades which are the full length of the finished blade ring and spacing blocks, and then uniting the built-up structure by fusion of metal.

10. The method of making a blade ring which comprises building it up around a sleeve from blades which are the full length of the finished blade ring and spacing blocks, uniting the structure in an initial manner, turning grooves in the rows of spacing blocks, winding metallic ribbon in said grooves, and then permanently uniting the structure by fusion of metal.

11. The method of strengthening a blade ring built up from blade lengths and spacing members which comprises cutting grooves around the spacing members and winding metallic ribbon therein.

12. The method of strengthening a blade ring built up from blade lengths and spacing members which comprises cutting grooves around the spacing members, winding metallic ribbon therein, and then uniting the layers of ribbon by fusion of metal.

In witness whereof, I have hereunto set my hand this first day of July, 1920.

CHRISTIAN STEENSTRUP.
